UNITED STATES PATENT OFFICE.

ALEXANDER S. SPEER, OF BUFFALO, NEW YORK, ASSIGNOR, BY MESNE ASSIGNMENTS, TO THE BEAVER PRODUCTS COMPANY, INC., A CORPORATION OF NEW YORK.

COMPOSITION ROOFING AND METHOD OF MAKING THE SAME.

Application filed December 28, 1920; Serial No. 433,623. Renewed October 9, 1922. Serial No. 593,461.

To all whom it may concern:

Be it known that I, ALEXANDER S. SPEER, a citizen of the United States, residing at Buffalo, in the county of Erie, State of New York, have invented certain new and useful Improvements in Composition Roofing and Methods of Making the Same; and I do hereby declare the following to be a full, clear, and exact description of the invention, such as will enable others skilled in the art to which it appertains to make and use the same.

My invention is an improvement in composition roofing and the like, and in methods of making the same, and relates more especially to the impressing of identifying data, as for instance trademarks and the like, on the roofing while it is in a warm and plastic condition.

An object of the invention is to provide a composition sheet or web having on one face at regular intervals impressions or designs cut in the said face.

Another object of the invention is to provide a method of making such impressions on the under face of the web or sheet, in such manner that while the impressions will be clear-cut and of sufficient depth to prevent obliteration in handling they will mark the one face only and will not in any manner mar the other face by offsetting the web or sheet or the like.

In the drawings—

Figure 1 is a perspective view of the printing and platen rolls.

Figure 2 is an enlarged transverse section of a part of the printing roll.

In the manufacture of composition roofing, it is desirable to impress data, as for instance a trademark, upon the under face, that is that face of the web or sheet which will not be exposed to the weather. It is also desirable, though not thought necessary, to make the impressions while the roofing is in course of manufacture, that is before it passes from the machine on which it is made. At this time the web or sheet is in a warm and plastic condition, and relatively soft, so that it is difficult to impress a mark of

sufficient depth to prevent obliteration in handling, without marring the opposite face of the web. If considerable pressure is used, that portion of the web containing the impression will be offset, presenting an embossed surface on the opposite face. 60

In order to obtain a clear-cut impression, without any offsetting of that portion of the web containing the impression, I use, for example, a die having raised printing characters of greater height than the depth of the impression desired, and I so limit the movement of this die toward the web during printing or impressing, that only a portion of the depth of the printing characters will enter the material of the web and the blank 65 surface of the die will not contact with the web. Thus the impression is cut in the web and any displacement of the material is lateral and not toward the opposite face. In order to prevent sticking of the material to 70 the die, I keep the surface of the die and of the roll upon which it is mounted lubricated by any suitable material, as for instance soap water, or kerosene.

In the manufacture of the composition 75 roofing, a body of felted material is provided, as for instance of shredded rags and the like, and this body is immersed in asphaltum of a suitable consistency and saturated therewith. One face is then faced 80 with pitch, and upon the pitch a mineral in a crushed state is placed, and in laying the roofing, it is this face having the crushed mineral which is to the weather. The impressions or designs are on the reverse face, 85 and the said designs or impressions are made while the finished web is warm and plastic.

In the drawings is illustrated one form of mechanism for performing the method above described. 90

In this mechanism, the web 1 as it passes from the machine on which it is formed, is passed between a pair of rolls 2 and 3, the former being a printing roll, while the latter is a platen roll, and one of the rolls is 95 mounted to yield away from the other, to compensate for various thicknesses of the web, and to prevent injury from lumps of

asphalt and the like which may be upon the web. The printing roll has upon the peripheral surface thereof a series of depressions 4, the depressions corresponding in spacing 5 and arrangement to the spacing and arrangement of the impressions desired upon the web. Within each of these depressions there is arranged a die 5, the said dies having printing characters 6 which extend 10 above the surface of the die in the usual manner, and these characters have sharp edges in order that they will cut the web and not merely indent it by displacing the material thereof toward the opposite face. 15 The characters are of greater height than the depth of the impression desired, and the blank surface of the die is spaced within the peripheral surface of the roll, so that that portion of the web which receives the 20 impression is engaged only by the printing characters, and not by the blank surface of the die. Thus there is no pressure on the web at this point other than the pressure of the printing characters themselves and there 25 is no tendency to displace the material of the web toward the opposite face. The printing roll may be arranged above or below the web, depending upon the character of the material being manufactured. For 30 instance roll roofing is cut with the weather or top side down, and in operating upon this material, the printing roll should be above. In cutting shingles from the web however, the weather side is up and the printing roll 35 should be below the web in order to impress the designs on the bottom of the web. In either case the printing roll is lubricated, with any suitable lubricant, as for instance soap water or kerosene, and in the arrangement shown the printing roll 2 runs in 40 contact with a roll 7 having a facing 8 of felt or like absorbent material. This facing is soaked with the lubricant, in any suitable manner.

45 In making the impressions, it is essential that they be alike, regardless of the thickness of the web and of its consistency. If the impression or design is cut too deeply, the web will tear, and if it is too shallow, 50 it will be obliterated in handling. The arrangement of the die as above described, with only those portions of the characters extending beyond the peripheral surface of the roll which actually penetrate the web 55 insures that the impressions will be cut to the same depth regardless of the thickness of the web and of its consistency.

I claim:

60 1. A method of impressing data on one face of sheets or webs of composition material without marring the other face, which consists in cutting the impression in the material by means of dies having raised 65 characters of greater height than the depth of the cut desired.

2. A method of impressing data on one face of warm and plastic sheets or webs of composition material without marring the other face, which consists in cutting the impression in the material by means of dies 70 having raised sharp edged characters of greater height than the depth cut desired.

3. A method of impressing data on one face of warm and plastic sheets or webs of composition material without marring the 75 other face, which consists in cutting the impression in the material by means of dies having raised characters of greater height than the depth of the cut desired and in limiting the depth of the cut by limiting 80 the movement of the dies toward the material.

4. A method of impressing data on one face of warm and plastic sheets or webs of composition material without marring the 85 other face, which consists in passing the sheets or webs between rolls one of which has dies depressed below the surface thereof and having printing characters extending 90 beyond the peripheral surface of the roll the depth of the impression desired.

5. A method of impressing data on one face of sheets or webs without marring the other face, which consists in subjecting the web to uniform pressure except at that point on which the impression is to be made and in making the impression at such points while the sheets or webs are supported on the other face.

6. A method of impressing data on one face of sheets or webs, without marring the other face which consists in cutting such data in the material while the sheet or web is subjected to uniform pressure about the impression and on the opposite face from the said impression.

7. A method of impressing data on one face of warm and plastic sheets or webs, without marring the other face, which consists in cutting such data in the material while the sheet or web is subjected to uniform pressure about the impression and on the opposite face from the said impression and in cutting said impression with raised characters carrying a suitable lubricant.

8. The method of applying identifying data, designs or the like to the face of sheets of the character described without marring or disturbing the opposite face of the material, which comprises cutting data or the like in said face on relatively thin lines or cuts, so as not substantially to displace or indent the material of the sheets toward the other face.

9. The method of applying identifying data, designs or the like to the face of relatively thin sheets of the character described without marring or disturbing the opposite face of the material, which comprises cutting data or the like in said face on rela-

tively thin lines by means of a sharp cutting edge while supporting said sheets on the opposite face.

10. The method of applying identifying data, designs or the like to the face of sheets of the character described without marring or disturbing the opposite face of the ma-

terial, which comprises forming the impressions for the outlines of such data or the like by narrow cuts which displace the material laterally but not substantially toward the other face of the sheet.

In testimony whereof I affix my signature.

ALEXANDER S. SPEER.
